UNITED STATES PATENT OFFICE.

ANNA B. BULLARD, OF BOSTON, MASSACHUSETTS.

GAME APPARATUS.

SPECIFICATION forming part of Letters Patent No. 243,688, dated July 5, 1881.

Application filed April 23, 1880. (No model.)

To all whom it may concern:

Be it known that I, ANNA B. BULLARD, of Boston, county of Suffolk, State of Massachusetts, have invented an Improvement in Game Apparatus, of which the following description, in connection with the accompanying drawing, is a specification.

This invention relates to an improved game apparatus in the nature of a puzzle, and designed for home or evening amusement.

My apparatus, viewed as an improved article of manufacture, comprises a set of at least six movable figures and a series of at least seven spots, spaces, or squares arranged on a horizontal surface, preferably a card, paper, or cloth, adapted to serve as or to be placed at the bottom of a box, thus making or constituting a receptacle to retain the movable figures and form a suitable box-like package.

Figure 1 represents the horizontal surface forming part of my game apparatus arranged within the bottom of a box, which, in practice, will have a cover to retain in the said box the movable figures, the seven spaces therein to be occupied by the movable figures being numbered and designated by the large circles, the said figure of the drawings showing within the said spaces by the smaller solid black and sectioned spots the two sets of movable figures or active members of my game apparatus. Fig. 2 represents the top of the box or cover, portraying movable figures arranged for forward movement and change of position in accordance with the plan of the game; and Fig. 3 is a cross-section of the box and lid with one of the figures within the box.

The object of the game is to provide at least two sets of movable figures, containing three figures in each set contrasted with each other in color or size, so as to appear as opponents, to place one set of these movable figures in three of the spaces at one end of the row of spaces, and the other set on the three spaces at the opposite end of the row, and by moving each one of the separate movable figures singly in one direction only or jumping one figure over the other cause the two sets of movable figures to exchange places or pass from one end of the line to the other over the intermediate space, each movable figure occu-

pying in its journey a separate space. This is seemingly an easy problem to solve, but without considerable thought is difficult to perform correctly, and the occupation affords amusement, and makes, therefore, a valuable game apparatus as a new article of manufacture, and one which will have great demand and sale. In practice I propose to make these movable figures to carry out the idea suggested in Fig. 2 of the drawings, and make half of them to represent toads and the other half frogs; but it is obvious that I might select other objects instead of toads and frogs, and might use checker-men or movable blocks.

I do not limit myself to the exact number of blocks, as more than those shown may be used.

In the drawings, *h* represents the horizontal surface, of paper, wood, or other suitable substance, forming the body of a box, with seven spaces, 1 2 3 4 5 6 7, therein portrayed, or delineated therein as large plain circles or lily-pads. One set of three movable figures is represented by the black spots *a b c* and the other set by the sectioned spots *d e f*, each set being arranged at its own end of the line of spaces, with the space 4 between them vacant.

The change of position can only be made as follows: move *d* to space 4, *c* to space 5, *b* to space 3, *d* to space 2, *e* to space 4, *f* to space 6, *c* to space 7, *b* to space 5, *a* to space 3, *d* to space 1, *e* to space 2, *f* to space 4, *b* to space 6, *a* to space 5, and *f* to space 3, or in the reverse order.

The cover of the box is marked *x*.

I claim—

As an improved article of manufacture, a game apparatus composed of a supporting or foundation surface or card having at least seven spaces and two sets of movable figures of at least three figures to a set, all as and for the purpose herein shown and described.

In testimony whereof I have signed my name to this specification in the presence of two subscribing witnesses.

ANNA B. BULLARD.
